United States Patent Office.

WILLIAM I. BUNKER, OF YANKTON, DAKOTA TERRITORY.

Letters Patent No. 97,757, dated December 14, 1869.

IMPROVEMENT IN LAMP-EXTINGUISHERS.

The Schedule referred to in these Letters Patent and making part of the same.

Be it known that I, WILLIAM I. BUNKER, of Yankton, county of Yankton, and Territory of Dakota, have invented a new and useful Lamp-Light Extinguisher; and I do hereby declare that the following is a full and exact description of the construction and operation of the same.

My invention consists in a horizontal slot, *a*, Figure 1, near the upper end, and on one side of the wick-tube of a lamp, this slot to be of any required width suitable to the size of the lamp, and extending from one side of the wick-tube to the other.

Also, from the upper and outside edge of this slot, I have a metal guard or cap, *b*, Figures 2 and 3, extending down over the slot, at an angle from the tube.

This cap and slot are for the purpose of conveying air to the flame, (after the wick is turned down below the slot in the wick-tube,) by which means the flame is extinguished.

What I claim as my invention, and desire to secure by Letters Patent, is—

A slot, *a*, in the side of the wick-tube, near the top, with a cap, *b*, extending down from the upper edge of the slot, at an angle from the tube, for the purpose of conveying the rising air to the flame.

WILLIAM I. BUNKER.
